UNITED STATES PATENT OFFICE.

JOHN M. GRIFFITH, OF PHILADELPHIA, PENNSYLVANIA.

PENCIL-SHARPENER.

SPECIFICATION forming part of Letters Patent No. 350,930, dated October 19, 1886.

Application filed October 24, 1885. Serial No. 180,809. (No model.)

To all whom it may concern:

Be it known that I, JOHN M. GRIFFITH, a citizen of the United States, residing at Philadelphia, in the county of Philadelphia and 5 State of Pennsylvania, have invented certain new and useful Improvements in Pencil-Sharpener, of which the following is a specification, reference being had to the accompanying drawings.

10 This invention has relation to pencil-sharpener; and it consists in certain features of construction hereinafter described, and particularly pointed out in the claim.

Referring to the drawings, Figure 1 is a 15 plan, and Figs. 2 and 3 are sections on the lines 1 2, 3 4, in Fig. 1, respectively, of a pencil-sharpener constructed in accordance with my invention.

Like letters indicate like parts in all the 20 figures.

A represents the sharpener proper, which consists of a plate of steel cut and cross-cut like a file to produce teeth or an abrading-surface, the cuts being made diagonally and 25 transversely to the length of the plate and at right angles to each other.

An aperture, B', in the handle B is convenient for suspending the sharpener.

As illustrated in Figs. 1, 2, and 3, the handle B is made of sheet metal, which is corrugated, as at B² B³, and provided with rounded edges B⁴, all of which serve to not only ornament the handle, but also to give additional strength thereto. A recess, B⁵, is reamed for 35 the reception of the plate A, the walls or flanges B⁶ serving, either with or without suitable cement, the purpose of retaining the plate within the handle.

The general object of the invention is to 40 provide a pencil-sharpener for the use of school children which shall be compact, simple in construction, capable of being produced at the slightest possible expense, and one which can be used in sharpening either lead 45 or slate pencils without soiling the hands, as either the sharpener may be held stationary

by one hand by the handle B and the pencil reciprocated and rolled thereon, or the pencil may be held and rolled in one hand while the sharpener is reciprocated thereon by the other. 50

Heretofore, when pencil-sharpener have been made of toothed steel plates, special shapes thereof have been required to form handle portions and suspension devices both for the article itself and for slates to which 55 said articles have been attached. Such constructions necessitate the special provision of portions of the steel which is not toothed. Pencil-sharpener have also been heretofore made of glass with integral handles or set in 60 handles of cast-brass. By my improvement a long bar of steel provided with an abrading-surface can be readily broken up into short pieces, which, by reason of its being brittle, are smooth enough at the ends without fur- 65 ther cutting or finishing. For a handle I utilize new scrap tin or other sheet metal, very small pieces otherwise wasted being sufficient, from which, by suitable dies, I cut out and simultaneously strike up a neat, strong handle having 70 flanges which are bent over the unfinished edges of the steel sharpener, so that a finished serviceable implement is produced at a very slight cost—an essential requirement of articles of this class.

Having described my invention, what I 75 claim is—

As an article of manufacture, a pencil-sharpener consisting of a rectangular piece of steel with broken unfinished ends, corrugated 80 upon one surface, and embedded in and having its ends and side edges covered by the flanges B⁶ of an integral sheet-metal backing and handle having strengthening corrugations B² B³ and rounded edges B⁴, substantially as 85 shown and described.

In testimony whereof I affix my signature in presence of two witnesses.

JOHN M. GRIFFITH.
